UNITED STATES PATENT OFFICE.

HENRY BRUNT, OF BALTIMORE, MARYLAND.

DESIGN FOR A EWER, &c.

SPECIFICATION forming part of Design No. 23,354, dated June 12, 1894.

Application filed May 18, 1894. Serial No. 511,722. Term of patent 3½ years.

To all whom it may concern:

Be it known that I, HENRY BRUNT, a citizen of the United States, residing at Baltimore, Maryland, have invented and produced a new and original Design for a Ewer or Jug, of which the following is a specification, reference being had to the accompanying drawings, forming a part hereof.

Referring to the annexed drawings, Figure 1 is an exterior side elevation of the ewer, and Fig. 2 a top view of the same.

I describe the ewer or jug as follows: Its body A from the base a flares outwardly in curved lines and is circular in cross section. At b its diameter is the greatest, and from that point to the upper end it is curved first inward and then outward, and reeded at the sides,—this portion forms the neck of the ewer. The

upper edge of the neck is scalloped as seen from either side, and the central reed is decorated by two small scrolls. The pouring lip B is set well back so that its extreme edge does not project much beyond the point b, and its sides are decorated with scroll work and leaves. The handle C is ornamented by scrolls and leaves, and it is connected to the neck at a point below the upper edge. Near the base is an ornamental band D formed of scroll work.

I claim as my invention—

The design for a ewer or jug as herein shown and described.

HENRY BRUNT.
